UNITED STATES PATENT OFFICE.

RICHARD WILLIAM CLERY, OF MARYBOROUGH, IRELAND.

ALARM-SIGNAL ARRANGEMENT FOR USE IN CONNECTION WITH RAILWAYS.

No. 823,668.

Specification of Letters Patent.

Patented June 19, 1906.

Application filed January 29, 1906. Serial No. 298,385.

To all whom it may concern:

Be it known that I, RICHARD WILLIAM CLERY, a subject of the King of Great Britain, residing at Sunnyside, Maryborough, Queen's county, Ireland, have invented certain new and useful Improvements in Alarm-Signal Arrangements for Use in Connection with Railways, of which the following is a specification.

- 10 This invention relates to improvements in alarm-signal arrangements for use in connection with railways, the object being to provide a cheap and simple device by means of which the driver and guard of a train, as well as the signalman in the point-box, can be informed when the train is tending to pass the "distance" signal, so that the former may be pulled up before entering the "home" section.
- 15 The invention is described with reference to the accompanying drawings, in which—
- Figure 1 is a side elevation, partly in section, of so much of a railway-engine as is necessary to illustrate the invention; Fig. 2, a front elevation of a signal-post; Fig. 3 a side elevation, 25 partly in section, on an enlarged scale, of the alarm-bell apparatus, while Fig. 4 is a plan of same through the top of the cab.

In carrying out the invention a rod *c*, which depends downward, is secured to the semaphore-arm *a* of the distance-signal post *b*, the lower end of such rod being slotted at *d* and coupled to the short arm *e* of a two-part lever pivoted to the signal-post *b*, the opposite end or long arm *f* of said two-part lever 35 projecting sufficiently forward over the rails *g* to be in line with the engine and carriages on said rails and at a slight distance above the general height of such. On the engine and also on the guard's van a tube or tubular 40 bracket *h* is secured, through which passes a spring wire or flexible arm or lever *i*. The preferred arrangement is to couple the rod or lever *i* to a bell-crank lever or arm *j*, the outer end of which is arranged to come in contact 45 with the arm *f* of the pivoted lever on the signal-post when the semaphore-arm is at "danger" or in the full-line position indicated in Fig. 2. The rod *i* and lever *j* are normally kept in the position indicated by dotted lines 50 in Fig. 1 by a spring *k*. The lower end of the rod *i* is coupled to a pivoted lever *l*, preferably arranged beneath the roof of the cab of the engine, the free end of the last-named lever engaging with the mechanism of a spring-controlled alarm-bell or gong *m*, located on 55 the engine or in the interior of the guard's van,

so that the driver or the guard may have his attention drawn to the fact that the signal is at "danger," thereby enabling him to stop the train before an accident can occur. A 60 suitable arrangement of alarm-bell mechanism for this purpose may consist of the bell *m*, a pivoted hammer *n*, provided with arms *o*, contacting with the teeth of a wheel *p*, mounted on a stud *q*, said wheel being controlled by 65 a spring *r*, which can be wound up in any suitable way to store up the necessary power for rotating the wheel to operate the hammer and give the alarm. Below the wheel suitable notches are provided with which the pivoted lever *l* may engage, so as to hold the wheel from rotating when the semaphore-arm *a* is in the "line clear" position indicated by the broken lines in Fig. 2. On the other hand, when the arm *f* is in the position 70 indicated in full lines in Fig. 2 the lever *j* engages with it, is depressed, and so releases the lever *l* from the notch in the wheel, allowing the gong or bell to be sounded to draw the attention of the driver or guard.

The arrangement of arms and levers is also in communication with an electrically-controlled alarm-bell located in the signal-box, so that as soon as contact is made in the manner previously indicated this bell is also 85 rung. The preferred arrangement for this purpose is to secure a pulley *s* on the arm *f* of the lever pivoted to the signal-post, so that when the lever *j* is being depressed by contact with the arm *a* the latter is slightly lifted 90 to enable the pulley *s* to come in contact with a bracket *t*, secured to the signal-post *b*. This bracket, and likewise the bracket *u*, on which the pivoted lever is mounted, are wired to an electric battery placed in a suitable position, and in which circuit an ordinary electric bell is also arranged. The operation described completes the circuit and rings the bell, which is located in the signal-box. An insulating-piece may be provided 100 on the bracket *t*, so that when the signal is lowered by the signalman to allow a train to pass the bell-circuit to the signal-box will be first made and then broken, thus avoiding the constant ringing of the bell while the signal-arm is down. The slot at the lower end of the rod *c* enables the pivoted lever *e* to be operated for ringing the signal-box bell without affecting the position of the semaphore-arm *a*. In place of the electrical contact arrangement described a spring-controlled button or the like may be arranged on the arm *f* 105 110

at a point to be engaged by the arm *j*, this button being wired in a suitable manner to the signal-cabin, as before described. In such a case the bracket *t* and pulley *s* would 5 be dispensed with.

The device is specially applicable during dark and foggy weather, and the arm *i* or lever *j* may be arranged to be withdrawn in clear weather, so as not to come in contact 10 with the lever *f*. When the signal shows "clear," the lever *f* is raised somewhat, so that the lever *j* does not come in contact therewith.

What I claim is—

- 15 1. In an alarm-signal device, the combination with a post and a semaphore-arm connected thereto, of a lever carried by said post and connected with said arm arranged and adapted to be contacted by means carried by a moving vehicle, an alarm mechanism carried by said vehicle and adapted to be set off by the movement of said means, and an electric circuit adapted to be closed by the movement of said lever.
- 20 2. In an alarm-signal device, the combination with a post and a semaphore-arm carried thereby, of means carried by said post and connected to said arm, arranged and adapted to be actuated by a moving vehicle and 30 when so actuated to close an electric circuit and to release an alarm mechanism carried by said vehicle.
- 25 3. In an alarm-signal device the combina-

tion with a signal-post carrying a pivoted semaphore-arm, of a lever pivoted to said post, a rod connecting one end of said lever with the semaphore-arms, means on the lever adapted to close the circuit of an electric alarm such means comprising a contact part on the signal-post and a contact part carried 35 by the lever for engaging therewith, spring-controlled means carried by a moving vehicle for raising said lever, means connected to said spring-controlled means, and an alarm-bell mechanism carried by the moving vehicle 40 and adapted to be controlled by said last-mentioned means.

4. In an alarm-signal device the combination with a signal-post and a semaphore-arm pivoted thereto, of a lever pivoted to said 45 post, a rod connecting one end of said lever with the semaphore-arm, means on the lever adapted to close an electric circuit for sounding a signal, spring-controlled means carried by a moving vehicle for engaging said lever, a further lever connected to said spring-controlled lever and an alarm-bell mechanism carried by the moving vehicle and adapted 50 to be controlled thereby.

In testimony whereof I have hereunto set 55 my hand in the presence of two subscribing witnesses.
